UNITED STATES PATENT OFFICE.

MAURICE P. SULLIVAN, OF NEWARK, NEW JERSEY, ASSIGNOR TO SPLITDORF ELECTRICAL COMPANY, OF NEWARK, NEW JERSEY.

SPARK PLUG.

Application filed May 20, 1920. Serial No. 382,787.

To all whom it may concern:

Be it known that I, MAURICE P. SULLIVAN, a citizen of the United States, residing at Newark, in the county of Essex, State of New Jersey, have invented certain new and useful Improvements in a Spark Plug, of which the following is a description, reference being had to the accompanying drawing and to the figures of reference marked thereon.

My invention relates to a spark plug more particularly of the non-grounded type, that is to say, one in which both the electrodes are insulated and brought out to suitable connecting devices. Such plugs are useful in so-called two-spark ignition systems, that is to say, where there are two sparks in series in one cylinder. For such purposes it is common practice to use one plug in which both terminals are insulated, such as in the plug shown and described herein, and a second plug of the usual type wherein only one electrode is insulated, the other being the shell of the plug or the engine itself.

One of the objects of my invention is to provide a plug of the above type which is rigid in construction and relatively cheap to manufacture.

My invention is set forth in a single figure of the attached drawing, which shows a sectional view through various parts of the plug, except the central electrode.

In the drawing 1 is a nut corresponding to the usual shell, having threads 2 at one end for the purpose of screwing the plug into an engine cylinder. The central hole through the nut 1 carries a tube shaped insulator 3, preferably of wound mica, the lower end of which rests against a head 4 of the sleeve electrode 5, the interior of which is preferably bored to taper to take a tapered central electrode 6, which is insulated from the interior wall of the sleeve 5 by an insulator 7, preferably of wound mica. The insulator 7 preferably extends at its lower end flush with the head 4 leaving an annular space 8 around the sparking terminal 9 which is fastened to the central electrode 6. The head 4 has fastened thereto a sparking terminal 10 which is formed to co-operate with the terminal 9. Positioned over the tube insulator 3 at its lower end and resting on the head 4 is a ring insulator 11, which is preferably made up of a series of mica washers 12, one of which only is indicated, the

balance of them being shown as a solid insulator. Positioned on the upper end of the tube insulator 3 is a second ring insulator 13, preferably of similar material to 11, that is to say made up of a series of mica washers 14, one only of which is indicated. It is to be understood of course that the insulators 11 and 13 may be of one piece material of any other suitable kind. It is to be noted that the insulators 11 and 13 rest against opposite faces of the nut 13 thereby holding it in longitudinal position on the tube insulator 3. Resting on the insulator 13 and making contact with the sleeve 5 at 15 is a connecting terminal ring 16 having terminal stud 17 securely fastened thereto and a nut 18 on the stud 17 for connecting the ignition wire thereto. Positioned over the upper end of the insulator 7 and the central electrode 6 is another insulator 19 which engages the connecting ring 16. The insulator 19 is preferably made up of a series of mica rings, one of which is shown at 20 and the washer 21 rests on the ring 19 and a clamping nut 22 engaging threads 23 on the upper end of the central electrode 6, draws the same securely within the electrode sleeve 5 and through the medium of the head 4 all of the parts are clamped securely to the nut or shell 1. The terminal nut 24 being used to secure any terminal that may be used between it and the clamping nut 22.

Having thus described my invention what I claim is:

1. In a spark plug, a one piece shell adapted to be screwed into an engine cylinder, said shell carrying a tube shaped insulator within its central opening and a ring of insulating material over the ends of the tube and immediately adjacent both ends of the shell, a metallic electrode sleeve within said tube insulator and having a head for engaging the lower of said ring insulators and a sparking terminal fastened to the head, said sleeve also having a tapered hole passing therethrough, a tapered central electrode pin fitted within the tapered hole but insulated from said sleeve and having a sparking terminal, spaced away from said pin insulator, a terminal connecting ring seated on the upper of said insulating rings and in annular engagement with said metallic sleeve, an insulator positioned over the central pin and resting on said connecting ring and means engaging the outer end of the

central pin to draw and hold together all of said parts.

2. In a non-grounded spark plug, a nut threaded at one end for screwing into an engine cylinder, said nut carrying; two concentrically arranged electrodes, one within the other but insulated one from the other and from the nut, and two spacing insulators engaging the nut on opposite faces, said 10 outer electrode having a relatively thick tapering head; a terminal connecting ring in electrical engagement with the outer of said electrodes and resting on the upper of said spacing insulators, an insulator above said 15 ring, the inner surface of said outer electrode

as well as the inner electrode being tapered, and means on the outer extremity of the inner electrode for drawing said tapered portions into normal operative position, the insulator between said concentrically arranged electrodes extending substantially flush with the outer electrode forming an annular space around the lower end of the inner electrode, a sparking terminal attached to said thick head of the outer electrode and extending 20 into sparking position with the central electrode.

In testimony whereof, I affix my signature.

MAURICE P. SULLIVAN.
